SPRAY GUN

Gustaf Gustafson, Yakima, Wash.

Application November 20, 1939, Serial No. 305,372

2 Claims. (Cl. 299—111)

My invention relates to improvements in spray gun nozzles for use in connection with a hose or pipe line, more particularly in spraying trees, plants, etc., with insecticide.

The principal object of the invention is to provide a spray gun assembly constructed and arranged to reduce to a minimum hydraulic friction therein and adapted for maximum flexibility, as regards control, to vary the density and velocity of the spray.

To the accomplishment of the above, and subordinate objects presently appearing, a preferred embodiment of my invention has been illustrated in the accompanying drawings, set forth in detail in the succeeding description and defined in the claims appended hereto.

In said drawings:

Figure 1 is a view in side elevation of the preferred embodiment of my invention,

Figure 2 is a fragmentary view partly in longitudinal section and partly in side elevation of the rear part of the gun drawn to an enlarged scale,

Figure 3 is a similar view of the front part of the gun,

Figure 4 is a view in front elevation of the spray-control member,

Figure 5 is a detail view in transverse section taken on the line 5—5 of Figure 3 looking in the direction indicated by the arrows,

Figure 6 is a view in perspective of the front end of the spray-control rod, and

Figure 7 is a view in longitudinal section taken on the line 7—7 of Figure 2 looking in the direction indicated by the arrows and drawn to an enlarged scale.

Referring to the drawings by numerals, the basic element of my improved gun is a tubular main barrel 1 having an enlarged internally threaded front end 2, and an externally threaded rear end portion 3 slightly reduced in diameter and formed with an internal worm thread 4. Forwardly of the rear end portion 3, said barrel 1 forms a pressure storage chamber 5 therein and is provided with an inlet nipple 6 for the attachment of said barrel to a hose, or pipe line, not shown, as through the medium of the usual coupling 7 threaded into the outer end of said nipple with a gasket 8 clamped between the same and an internal shoulder 9 in the nipple. The nipple 6 inclines forwardly to the barrel 1 for a purpose which will be apparent.

Detachably connected, as presently described, to the front end 2 of the barrel 1 to extend forwardly and axially therefrom is an elongated nozzle tube 10 slightly smaller in diameter than

that of the chamber 5. The connection between the nozzle tube 10 and barrel 1 comprises an annular coupling 11 threaded onto the rear end of said tube and into said front end 2 of barrel 1, said coupling 11 being of the same internal diameter as said tube 10. The coupling 11 also functions as a jamb nut to clamp a disk-like annulus 12 into the front end 2 of the barrel 1 against an internal shoulder 13 formed by the juncture of said end and barrel, said annulus being of suitable metal and forming a small valve seat 14 concentric to the chamber 5 and tube 10, a resilient gasket 15 being interposed between said annulus 12 and coupling 11. As will be readily seen, the annulus 12 is reversible so that either side thereof may form the seat 14 whereby a new seat may be readily provided in case one becomes worn.

The front end of the nozzle tube 10 has threaded therein a forwardly extending and tapering nozzle type spray head 16 provided with a reduced externally threaded front end 17. The head 16 is provided intermediate its ends with an internal transversely flat annular seat 18, and tapers internally to said seat, as at 19, in the rear thereof and also forwardly of said seat, as at 20, to a restricted outlet 21. The tapered portion 20 has a particular function presently seen. An outwardly flaring spray deflector nipple 22 is threaded onto the end 17 of the head 16 with a resilient gasket 22' interposed between the same and said end.

Extending through the barrel 1, to within a short distance of the end 2, is a valve control rod 23 having the rear end thereof extending rearwardly of said barrel and provided with a cylindrical, knurled hand grip 24 suitably fixed on said rod by a nut 25 and having within the rear end 3 of said barrel 1 a worm section 23' thereon turning in the threads 4, whereby said rod may, under rotation of said hand grip 24 in opposite directions, be fed forwardly and rearwardly. A packing gland 26 is threaded onto the rear end 3 of the barrel 1 with a gasket 27 and packing 28 therein for preventing leakage past said end.

Threaded part way onto the front end of the valve control rod 23 is a coupling sleeve 29 having an enlarged front valve end 30. Threaded into the front end of coupling sleeve 29 is the rear end of a spray-control rod 31. Sleeved onto the control rod 31 against the front end of the valve end 30 of sleeve 29 is a resilient valve washer 32 adjustably clamped against said front end by means of a sleeve 33 threaded onto rod 31 and provided with a front nut terminal 34. The

valve washer 32, as will be clear, is arranged to be engaged with and disengaged from the valve seat 14.

The spray control rod 31 extends forwardly into nozzle tube 10 to substantially the front end thereof and has slidably mounted thereon a spray-control member in the form of a longitudinally ribbed sleeve 35 slidably fitted in the nozzle tube 10 and having extending from the front end thereof a spray-control valve member 36. The valve member 36 comprises an intermediate, spirally grooved circular flange 37 fitting in the before described seat 18, slidably, a rearwardly tapering neck 38 between said flange 37 and sleeve 35, and a forwardly tapering tip 38 fitting loosely in the tapered part or portion 20 of spray head 16. A coil spring 39 sleeved onto said rod 31 between the sleeve 35 and a cotter pin 40 in said rod urges the sleeve 35 forwardly on the rod and hence the flange 37 onto seat 18 and the tip 38 into the tapered portion 20 of spray head 16. Sliding movement of the sleeve 35 on the rod 31 is limited by a longitudinally extending slot 41 in said rod and a cotter pin 42 extending through said sleeve and slot.

As will now be seen, under manipulation of the hand grip 24, the valve-control rod 23 may be adjusted endwise in opposite directions to adjust the valve washer 32 toward and from the seat 14 to control the volume of liquid entering the chamber 5 and passing to the spray head 16. By detaching the coupling 11, and gasket 15, the annulus 12 may be reversed to present a new valve seat 14 as required. The liquid passing between the ribs of sleeve 35 is directed through the grooves of flange 37 whereby it is caused to swirl as it emerges through outlet 21. By virtue of the described arrangement of the sleeve 35 on said rod 31, the valve washer 32 may be backed off the seat 14 while the flange 37 and tip 38 are held by the spring 39 in the described position in the spray head 16, thereby providing for increase of volume and pressure to head 16 causing the spray to spread in a wide stream which may be varied at will. By backing off valve washer 32 from seat 14 until spray-control rod 31 picks up the sleeve 35, through the slot 41 and cotter pin 42, the flange 37 may be backed off of seat 18 and the tip 38 withdrawn from the tapered part 20 of the head 16 thereby providing for creating a long narrow spray stream also variable at will. By turning the coupling 29, the rods 23 and 31 may be disconnected to disassemble the parts as will be clear. Also by adjusting the coupling 29 the rods 23, 31 may be adjusted endwise, relatively, to compensate for wear in valve washer 32, seat 14, gasket 22, and between flange 37 and seat 18.

The foregoing will, it is believed, suffice to impart a clear understanding of my invention without further explanation.

Manifestly the invention, as described, is susceptible of modification without departing from the inventive concept and right is herein reserved to such modifications as fall within the scope of the subjoined claims.

What I claim is:

1. In a spray gun, a tubular barrel having a

fluid inlet nipple extending therefrom intermediate its ends, an annular disk detachably mounted in the front end of said barrel and forming a reversible valve seat, a nozzle tube detachably secured at one end in said front end of said barrel and terminating at its opposite end in a conical spray head, a control rod threaded into the rear end of said barrel for endwise movement under turning and provided with a hand grip in the rear of said barrel for turning the same, a coupling sleeve threaded onto the front end of said rod for endwise movement therewith in the rear of said seat, a second rod threaded into said sleeve and extending into said nozzle tube for endwise movement with the second-mentioned rod, a valve washer fixed on the second-mentioned rod for engagement and disengagement with said seat under endwise movement of said rods, and a spray control member on the front end of the second-mentioned rod extending into said head and adjustable under endwise movement of said rods to vary its position in said head, said rods being endwise adjustable relatively under turning of said coupling sleeve to vary the normal relation of said washer and spray-control member, said second-mentioned rod having a lost motion connection with said spray control member whereby under endwise movement of said rods said washer is first disengaged from said seat and said spray control member subsequently adjusted.

2. In a spray gun, a tubular barrel having a fluid inlet nipple extending therefrom intermediate its ends, an annular disk detachably mounted in the front end of said barrel and forming a reversible valve seat, a nozzle tube detachably secured at one end in said front end of said barrel and terminating at its opposite end in a conical spray head, a control rod threaded into the rear end of said barrel for endwise movement under turning and provided with a hand grip in the rear of said barrel for turning the same, a coupling sleeve threaded onto the front end of said rod for endwise movement therewith in the rear of said seat, a second rod threaded into said sleeve and extending into said nozzle tube for endwise movement with the first-mentioned rod, a valve washer fixed on the second mentioned rod for engagement and disengagement with said seat under endwise movement of said rods, and a spray control member on the front end of the second-mentioned rod extending into said head and adjustable under endwise movement of said rods to vary its position in said head, said rods being endwise adjustable relatively under turning of said coupling sleeve to vary the normal relation of said washer and spray-control member, the second-mentioned rod having a lost motion connection with said spray control member whereby under endwise movement of said rods said washer is first disengaged from said seat and said spray control member subsequently adjusted, said spray-control member including a longitudinally ribbed sleeve slidably in said valve.
